SULPHUR RECOVERY

Fred M. Nelson, Newgulf, Tex., assignor to Texas
Gulf Sulphur Company, a corporation of
Texas

Application October 18, 1934, Serial No. 748,792

5 Claims. (Cl. 262—3)

This invention relates to the recovery of sulphur and has for its object the provision of an improved method and apparatus for recovering sulphur from underground deposits of elemental sulphur.

In the recovery of sulphur from deposits disposed beneath the surface of the earth, the so-called underground fusion or Frasch process is generally employed. In accordance with this process as it has heretofore been practised, a hole or well is drilled through the strata overlying the sulphur formation and is cased. A smaller hole is drilled below this casing to extend the well to a suitable depth into the sulphur formation. A system of co-axially arranged conduits is set through the casing and the smaller hole extending therebelow to the bottom of the well to provide a series of annular conduits communicating with the sulphur deposit and the surface of the ground. Through at least one of these annular conduits, generally the outermost, superheated water is introduced into the deposit, where it contacts and melts the sulphur. The melted sulphur collects in a body at the base of the well, where it enters the lower portion of another of the annular conduits, hereinafter referred to as the sulphur discharge conduit.

Air is introduced into the body of molten sulphur in the lower portion of the sulphur discharge conduit through one of the co-axial conduits, generally the innermost, to produce a mixture of sulphur and air having an average density sufficiently low so that the pressure exerted by the superheated water upon the body of molten sulphur will raise it to the surface of the ground, in accordance with the familiar principle of the air lift. Enough air is introduced so that the sulphur will not only be raised or pumped substantially to the level of the ground, but will be forced through suitable conduits to a reservoir, or to the top of a vat, where it may cool and solidify.

When substantially all of the melted sulphur has been discharged from the well, the sulphur discharge conduit, in addition to the outer annular conduits, is employed to introduce superheated water into the well to melt a further quantity of sulphur.

Operation of this process in the manner described above has been found to be accompanied by a number of disadvantages. For example, when liquid melted sulphur, under pressure and at high temperatures, is mixed with air, water, steam and other substances such as are commonly found in sulphur deposits, acids of an ex-

tremely corrosive nature, such as sulphuric acid, are formed. These acids attack and may destroy the sulphur discharge conduit in the well, the conduits through which the sulphur is carried from the well to the reservoir or to the vat, and other metal parts with which they come in contact.

Furthermore, when operating in the above described manner, steam and air separate from the sulphur in the conduits leading to the reservoir or vat, causing "hammers" which not only subject the pipe line to severe physical strain, but which also rupture any surface-protecting coating which has formed on the walls of the conduit, with the result that fresh surfaces of metal are exposed to the attack of the corrosive substances present in the sulphur.

The mixture of sulphur with air, water, steam, gas and fumes, together with other substances present in the sulphur as it is discharged from the well, has a volume several times greater than that of the sulphur itself. Consequently, larger conduits must be provided to transport the mixture, and a greater pressure is required to force it through the conduits, than would be required to handle the sulphur alone. Furthermore, since the pressure which can be applied to the body of molten sulphur at the base of the well is limited by the porosity of the formation in which the sulphur deposit occurs, it is necessary to increase the amount of air employed in the air lift, and thus still further to increase the volume of the sulphur-air mixture, if the mixture is to be pumped for any considerable distance. The importance of these considerations becomes apparent when it is realized that the reservoir or vat to which the sulphur is pumped may be at a distance up to several miles from the well.

Another important disadvantage to the above-described process as it is generally practised is owing to the fact that the sulphur in the deposit contains a varying amount of impurities comprising oils and other carbonaceous materials. When the sulphur is melted, these oils and other carbonaceous materials begin to discolorize it. The longer the sulphur is held in the molten state, the darker it becomes, even when the amount of oils and other carbonaceous materials is very small. If the superheated water which is introduced into the deposit melts the sulphur faster than it can be pumped from the well, this discolorization may assume serious proportions, for in such a case the melted sulphur accumulating at the base of the well becomes dark, and it in

turn darkens all of the sulphur produced by the well.

In accordance with the present invention, it is possible to overcome the foregoing disadvantages to the underground fusion process for the recovery of sulphur by separating from the sulphur as it emerges from the well those substances which are admixed therewith and which have densities less than that of the melted sulphur itself. The separation of these substances, comprising chiefly air, water and steam, from the melted sulphur greatly reduces the volume of material which must be handled beyond the well-head, with the result that smaller conduits may be employed to transport the sulphur to the reservoir or vat, and less air is required in the air lift to provide for the pumping of the sulphur. Furthermore, it is possible to increase the capacity of the air lift pump, and, therefore, to decrease the length of time during which molten sulphur is maintained in contact with the oils and other carbonaceous impurities of the deposit, with the result that a sulphur product of high purity and bright color may be obtained. In addition, the productive capacity of the well may be increased, and the life of the equipment employed may be prolonged.

The separation of the air, water and steam from the molten sulphur is brought about in a separating chamber located between the reservoir or vat and the well-head and preferably near the well-head. The molten sulphur from the well, together with the substances admixed therewith, is introduced into the separating chamber, wherein the melted sulphur settles to the bottom and the air, water and steam rise to the top and are withdrawn. The pressure exerted by the substances introduced into the separating chamber is utilized to force the molten sulphur from the collecting chamber to a reservoir or vat, in which it may be allowed to cool and solidify.

Other substances than air, water and steam which have densities less than that of melted sulphur and which are admixed therewith when it is introduced into the separating chamber, may also be separated from the melted sulphur. Air, water and steam comprise the chief substances separated, however, and particular reference will be made to them, but it will be understood that in the specification and in the appended claims the words "air, water and steam" are intended to include all substances having densities less than that of the melted sulphur which are admixed therewith as it is discharged from the well and which separate therefrom in the separating chamber.

The invention will be better understood from the following description, taken in connection with the accompanying drawings, in which

Fig. 1 is an elevation, partly in section, of an apparatus adapted for the practice of and embodying the invention; and

Figs. 2 to 4, inclusive, show apparatus of the type illustrated in Fig. 1 provided with modified valve arrangements.

The apparatus shown in Fig. 1 of the drawings comprises a vertically disposed separating chamber 10 having an inlet conduit 11 through which molten sulphur and substances admixed therewith may be introduced from the sulphur well into the separating chamber. The inlet conduit 11 is preferably an extension of the sulphur discharge conduit leading from the bottom of the well. A short conduit 12 and an outlet conduit 13 provide for the removal of molten sulphur from the lower portion of the separating cham-

ber to a reservoir or vat for sulphur (not shown).

The entire separating chamber is surrounded by a steam jacket 14, into which steam from a suitable source may be introduced through conduits 15 and 16. The conduit 15 preferably extends through the outlet conduit 13 substantially in axial alignment therewith to a point adjacent the reservoir or vat. The conduit 15 emerges from the interior of the sulphur conduit 13 through a packing gland 17.

Conduits 18 and 20 provide for the escape of steam from the steam jacket 14 and for introducing it into a conduit 21, which passes through a packing gland 22 and the separating chamber 10 into the inlet conduit 11. The conduit 21 extends through the inlet conduit in substantially axial alignment therewith to some convenient point, for example, to the well-head. Steam passing through the conduits 15 and 16, the steam jacket, and the conduits 18, 20 and 21 in the direction indicated by the arrows serves to maintain sulphur passing through the outlet conduit 13, the separating chamber 10, and the inlet conduit 11 in the molten state.

An orifice 23 in the upper portion of the separating chamber 10 provides for the escape of the air, water and steam which separates from the sulphur in the separating chamber. A conduit 24 communicating with a chamber 25 above the orifice 23 permits withdrawal of the mixture of air, water and steam which passes through the orifice.

In the valve structure shown in Fig. 1, a needle valve 26 operated by a float 27 is employed to close the orifice 23. Surmounting the float and firmly attached thereto is a holder 28 provided with transverse bars or plates 30. A stem 31, supporting upon its upper end portion the needle valve 26 and carrying upon its lower end portion a button 32, is positioned within the holder and extends through holes in the transverse bars 30 thereof. The length of the stem 31 between the needle valve and the button is somewhat greater than the distance between the transverse bars or plates, and it is therefore possible for the stem 31 to slide axially back and forth through the holes. Preferably the diameter of the holes is a trifle greater than the diameter of the stem 31, so that the stem and needle valve 26 may move transversely to a slight extent to insure proper seating of the valve when it is raised by the float to the closed position. The button 32, the diameter of which is greater than that of the holes, prevents the accidental withdrawal of the stem from the holder.

A plug 33, through which the orifice 23 extends, is detachably mounted in a supporting plate 34. The supporting plate is in turn detachably mounted on a closure plate 35, and the whole assembly is adapted to engage with an end plate 36 to close the upper portion of the separating chamber 10.

A removable cap 37 serves to close the chamber 25 above the orifice. By removing the cap, access may be had to the orifice assembly and the valve for repairs or replacements.

A sleeve 38, the upper portion of which is perforated, extends downwardly from the closure plate 35 and surrounds the upper portion of the holder 28 to provide a guide therefor. A perforated cylinder 39 extends downwardly from the end plate 36 and surrounds the float 27 to guide its movement. A transverse bar 40 is mounted in the lower end of the perforated cylinder 39 to support the float in its lowermost position.

In the modified valve structures shown in Figs. 2 to 4, the orifice 23 extends through a plug 42 which engages with an end plate 43 of the separating chamber 10. A stem 44 passes through the orifice and supports on either side thereof valves 45 and 46 adapted to seat in the plug 42 and thereby to close the orifice. The upper portion of the stem 44 extends to a point above the uppermost valve 45. The length of the stem between the valves 45 and 46 is greater than the length of the orifice, so that axial movement of the stem through the orifice is possible and so that not more than one valve may be closed at a time. The diameter of the stem is substantially less than the diameter of the orifice so that when the stem is in a mid-position and both valves are open, air, water and steam may escape through the annular passage between the orifice walls and the stem.

20 The chamber 25 above the orifice is closed by a removable cap 47. The upper portion of the stem 44 extends through the chamber 25 and through a packing gland 48 in the cap 47.

Means operatively associated with the upper portion of the stem 44 provide for axial movement thereof so that the valves 45 and 46 may be opened and closed. In the apparatus shown in Fig. 2, these means comprise a compression spring 50 engaging the upper surface of the packing gland 48 and the under surface of a washer 51 which is firmly attached to the stem. The spring tends to lift the stem and to hold the lowermost valve 46 in a closed position against its seat in the plug 42.

35 The upper end portion of the stem extends through a solenoid 52 which is electrically connected to a source of current and which may be controlled by a rheostat 53 or in any other suitable manner. The uppermost end portion of the stem adjacent the upper portion of the solenoid comprises a magnetic material such as iron, whereas the stem below this portion is non-magnetic. When no current is passing through the solenoid, the stem is lifted by the spring 50 and the non-magnetic portion of the stem is held so that it extends substantially into the solenoid, with the magnetic portion of the stem extending thereabove.

When current is passed through the solenoid, the magnetic portion of the stem is drawn downwardly into the solenoid against the action of the spring 50, whereby the lower valve 46 is opened and the upper valve 45 is forced into a closed position against its seat in the plug 42. 55 By controlling the current passing through the solenoid, it is possible to control the pressure with which the upper valve 45 is held closed.

In the modified valve structure shown in Fig. 3, the valves 45 and 46 are operated by means of fluid pressure applied above a diaphragm 55. The upper end portion of the stem 44 is attached to the diaphragm substantially at its center, and the diaphragm, when no fluid pressure is applied thereabove, exerts an upward force on the stem to hold the lower valve 46 against its seat in the plug 42.

When fluid pressure is applied above the diaphragm 55, the stem 44 is forced down until the upper valve 45 is seated in a closed position against the plug 42. By controlling the fluid pressure exerted upon the diaphragm, for example by means of a valve 56, it is possible to control the pressure with which the upper valve 45 is held closed.

75 In the modified valve structure illustrated in

Fig. 4, a compression spring 60 engages the upper surface of the packing gland 48 and the under surface of a washer 61 which is firmly attached to the stem 44. The spring exerts an upward force on the stem and tends thereby to hold the lower valve 46 in a closed position against the plug 42.

A lever 62 is pivoted adjacent one end to a supporting member 63. A hinge member 64 engages the upper end portion of the stem 44 above the washer 61, and the lever is pivoted thereto at its fulcrum. A weight 65 is mounted upon the outer portion of the lever beyond its fulcrum at the hinge member 64, and is adapted to slide thereupon.

When the weight is moved to the outer end portion of the lever away from its fulcrum, the lever forces the stem 44 down against the pressure exerted by the spring until the upper valve 45 engages its seat in the plug 42. By regulating the distance of the weight from the fulcrum of the lever at the hinge member 64, it is possible to control the force with which the upper valve 45 is held in a closed position.

The operation of the apparatus shown in Fig. 1 is as follows: Molten sulphur from the well, together with the air, water and steam admixed therewith, is pumped into the separating chamber 10 through the inlet conduit 11. The molten sulphur settles to the bottom of the separating chamber and the air, water and steam, which have densities substantially less than that of the molten sulphur, rise to the surface thereof. The molten sulphur enters the short conduit 12 and the outlet conduit 13, while the air, water and steam pass through perforations in the cylinder 38 and the sleeve 39 and through the orifice 23 into the chamber 25. From the chamber 25 these substances are withdrawn through the conduit 24 to suitable collecting tanks (not shown), or they may be discharged into the atmosphere.

Generally, the molten sulphur will be pumped into the separating chamber more rapidly than the static pressure therein can force it through the outlet conduit 13. Consequently, a body of molten sulphur accumulates within the separating chamber until it attains a depth at which the float 27 and the needle valve 26 operated thereby begin to rise. As molten sulphur continues to accumulate within the separating chamber, the float and needle valve are lifted until the orifice 23 is closed. Further introduction of molten sulphur, air, water and steam into the separating chamber increases the pressure therein, with the result that the molten sulphur is forced through the conduits 12 and 13 to the reservoir or vat.

During this phase of the operation, the level of the sulphur within the separating chamber, and with it the float 27, is lowered. The needle valve is held in the orifice by the pressure exerted thereupon by the air and steam until the float has descended to such a point that the lowermost of the transverse bars or plates 30 engages the upper surface of the button 32 at the lower end of the stem 31. Thereupon the weight of the float pulls the needle valve from its seat in the plug 33, the air, water and steam pass through the orifice, relieving the pressure within the separating chamber, and the needle valve drops back to its original position in relation to the float. The entire operation is repeated as molten sulphur continues to enter the separating chamber.

When substantially all of the melted sulphur has been pumped from the well, it is expedient to introduce superheated water into the deposit through the sulphur discharge conduit in the well. This is accomplished by admitting water under pressure to the outlet conduit 13. The water flows therethrough to the separating chamber, in which it rises until the float and needle valve are lifted sufficiently to close the orifice. The water then flows through the inlet conduit 11 to the sulphur discharge conduit and thence to the sulphur deposit. When a sufficient quantity of sulphur has been melted in the well, the supply of superheated water to the outlet conduit 13 is shut off and pumping operations are resumed.

The operation of the various modifications shown in Figs. 2-4 is substantially the same as the operation of the apparatus illustrated in Fig. 1, differing therefrom only in so far as is required by the different valve construction.

During the pumping operations, a downward force is applied to the stem 44 by electromagnetic action, fluid pressure or the lever and weight mechanism, substantially as described above, to hold the upper valve 45 in its closed position against the plug 44. Sulphur, admixed with air, water and steam, enters the separating chamber 10 through the inlet conduit 11. The sulphur settles to the bottom of the chamber, and the air, water and steam, owing to their lower densities, collect above it. As the sulphur continues to enter the separating chamber, the pressure therein is increased and the sulphur at the bottom of the chamber is forced through the short conduit 12 and the outlet conduit 13 to the reservoir or vat.

When substantially all of the sulphur in the separating chamber has thus been forced out, a mixture of sulphur with air, water and steam enters the conduits 12 and 13. Because a greater pressure is required to force this mixture through the conduits than is required for sulphur alone, a greater pressure begins to develop within the separating chamber. This greater pressure is sufficient to overcome the downward pressure holding the upper valve 45 closed, and it is accordingly forced open, allowing the air, water and steam to escape through the orifice to the chamber 25, whence they are withdrawn through the conduit 24. When enough air, water and steam have escaped from the separating chamber to reduce the pressure therein to a value below that required to hold the valve 45 opened, it is again closed and the operation is repeated.

When substantially all of the melted sulphur has been pumped from the well, superheated water may be introduced into the sulphur deposit through the sulphur discharge conduit. This is accomplished by releasing the force acting downwardly on the stem 44 and allowing it to be lifted by the spring or the diaphragm, substantially as described, to close the lower valve 46. Thereupon, superheated water may be admitted to the outlet conduit 13, through which it flows to the separating chamber. From the separating chamber it passes through the inlet conduit 11 and the sulphur discharge pipe to the sulphur deposit. When sufficient sulphur has been melted, the pumping is resumed and the cycle of operations is repeated.

The use of the invention permits of marked economy in the amount of air consumed in pumping sulphur. As an example of the efficiency of the invention, the following data relating to the

operation of a sulphur well located about 2000 feet from the reservoir are presented:

Pumping rate	With separator	Without separator	5
	20 tons sulphur per hour max.	14 tons sulphur per hour max.	
Free air consumption per ton of sulphur produced when operating the well at a rate of 14 tons per hour	.....	.....	10
	About 400 cu. ft.	About 1500 cu. ft.	

Other economies may also be effected by the use of the invention. For example, it is possible to reduce the size of the conduits leading to the sulphur reservoir, and the life of these conduits is prolonged by reducing the quantity of corrosive materials in the sulphur transported through them. By increasing the rate at which the sulphur may be pumped from the well, use of the invention increases the productive capacity thereof and results in the production of sulphur of a higher degree of purity and of a brighter color than could otherwise be produced.

I claim:

1. In a process for recovering sulphur from an underground deposit which involves introducing superheated water or steam into the deposit to produce a mixture comprising molten sulphur, air and water, the improvement which comprises introducing the mixture under pressure into a separating chamber substantially immediately upon its emergence from underground, separating the molten sulphur from the air and water in the separating chamber, separately withdrawing the molten sulphur and the air and water from the chamber, and controlling the rate at which air and water are withdrawn from the separating chamber to maintain therein adequate pressure for forcing the molten sulphur from the separating chamber and through a conduit.

2. In a process for recovering molten sulphur from an underground deposit which involves producing a mixture of molten sulphur with substances of lesser densities than molten sulphur, the improvement which comprises introducing said mixture under pressure into a separating chamber substantially immediately upon emergence of the mixture from underground, separating the molten sulphur from the substances of lesser densities in the separating chamber, separately withdrawing the molten sulphur and the separated substances from the separating chamber, and controlling the rate at which said separated substances are withdrawn from the separating chamber to maintain therein adequate pressure for forcing the molten sulphur from the separating chamber and through a conduit.

3. In a process for recovering sulphur from an underground deposit which involves introducing superheated water or steam into the deposit to produce a mixture comprising molten sulphur, air and water, the improvement which comprises introducing the mixture as it is discharged from the well under pressure into a separating chamber, maintaining the mixture in the separating chamber under superatmospheric pressure, separating the molten sulphur from the air and water in the separating chamber, separately withdrawing the molten sulphur and the air and water from the chamber, and maintaining adequate pressure in the separating chamber to force the molten sulphur from the separating chamber through a conduit by controlling the rate at

which air and water are withdrawn from the separating chamber.

4. In a process for recovering sulphur from an underground deposit which involves introducing superheated water or steam into the deposit under pressure to produce a mixture comprising molten sulphur, air and water and elevating said mixture to the surface of the earth by the pressure exerted by the introduced superheated water or steam, the improvement which comprises introducing the mixture discharged from the well into a separating chamber, maintaining said mixture in the separating chamber under super-atmospheric pressure due to the pressure of the superheated water or steam introduced into the deposit to produce said mixture and to elevate it to the surface of the earth, permitting the heavier molten sulphur of the mixture to settle to the bottom of the separating chamber, forcing said molten sulphur from the bottom of separating chamber through a conduit by means of the super-atmospheric pressure maintained in said separating chamber, and separately withdrawing separated air and water from the separating chamber.

5. In a process for recovering sulphur from an underground deposit which involves introducing superheated water or steam into the deposit under pressure to produce a mixture comprising molten sulphur, air and water and elevating said mixture to the surface of the earth by the pressure exerted by the introduced superheated water or steam, the improvement which comprises introducing the mixture discharged from the well into a separating chamber, maintaining said mixture in the separating chamber under super-atmospheric pressure due to the pressure of the superheated water or steam introduced into the deposit to produce said mixture and to elevate it to the surface of the earth, permitting the heavier molten sulphur of the mixture to settle to the bottom of the separating chamber, forcing said molten sulphur from the bottom of separating chamber through a conduit by means of the super-atmospheric pressure maintained in said separating chamber, and controlling the pressure in said separating chamber by controlling the rate at which air and water are withdrawn from said separating chamber.

FRED M. NELSON. 25
